CLAIM

The ornamental design for a pet water filter fountain, as shown and described.

DESCRIPTION

FIG. 1 is a front elevation view of a pet water filter fountain showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top, front perspective view thereof.

The broke lines illustrate portions of the pet water filter fountain that form no part of the claimed design.
